UNITED STATES PATENT OFFICE.

JOHN A. LAMONT, OF CHICAGO, ILLINOIS, ASSIGNOR TO AMERICAN STEEL FOUNDRIES,
OF CHICAGO, ILLINOIS, A CORPORATION OF NEW JERSEY.

RAILWAY-CAR-TRUCK ARRANGEMENT.

1,390,362.

Specification of Letters Patent. Patented Sept. 13, 1921.

Application filed April 25, 1921. Serial No. 464,112.

To all whom it may concern:

Be it known that I, JOHN A. LAMONT, a citizen of the United States, residing at Chicago, in the county of Cook and State of Illinois, have invented certain new and useful Improvements in Railway-Car-Truck Arrangements, of which the following is a specification.

This invention relates to a railway car truck arrangement and more particularly to six-wheel equalizing trucks and is an improvement on the arrangement disclosed in my copending application Serial No. 433,416 filed December 27, 1920.

One object of the invention is to further simplify and improve equalizing arrangements for railway car trucks and especially those of the six-wheel type.

Another object is to simplify the arrangement whereby the loads are transmitted from equalizing levers to the associated journal box in a manner to provide increased clearance at the intermediate journal box to accommodate longitudinal movement of the equalizing mechanism including the equalizing levers.

These and other objects are accomplished by means of the arrangement disclosed on the accompanying sheet of drawings in which—

Figure 1 is a fragmentary vertical longitudinal sectional view through the side frame and associated parts of a six-wheel truck embodying my invention;

Fig. 2 is a fragmentary horizontal longitudinal sectional view taken in the plane of line 2—2 of Fig. 1; and

Fig. 3 is a transverse vertical sectional view taken in the planes of the irregular line 3—3 of Fig. 1.

The various novel features of my invention will be apparent from the following description and drawings and will be particularly pointed out in the appended claims.

Referring to the figures of the drawings, it will be noted that I have disclosed my invention in connection with a railway car truck of the six-wheel type and including a truck side frame 10 having end pockets (not shown) for the reception of end journal boxes and an intermediate pocket 11 for the reception of a middle journal box 12. This journal box has a main box portion for the reception of a journal 13 and outwardly ex-

tending open ended hollow wings at each side thereof and each including side walls 14, which at their outer ends are connected by end walls 15 which engage either the side walls 16 which coöperate to form the intermediate journal box pocket 11 or engage the steel wear plates 17 secured thereto for guiding the journal box 12 in its relative vertical movements.

The main central body portion of the journal box 12 is provided with an integrally formed top or cover 18 upon which are directly mounted coil springs 21 and 22 which are concentrically arranged with respect to each other, the coil springs 21 being within the coil springs 22 and being mounted over integrally formed upstanding projections 23 on the top 18 of the journal box for the purpose of holding the springs in place. Coöoperating to perform this function, the top 18 of the journal box 12 is provided also with a central rib 24 which has a curved contour conforming to the curve of the coil springs 22. Mounted on top of these springs and bridging the sets of same is a spring cap 25 in which are vertically slidably mounted two plungers or auxiliary spring caps 26, the lower portions of which bear directly upon the inner relatively light coil springs 21 and the stems 85 of which are engaged by the lower surface of an equalizing beam 27, having a pivotal rocker projection 28 which is received within a pivot pocket 29 formed in the middle of the spring cap 25 whereby there may be 90 a relative rocking movement between the spring cap 25 and equalizing beam 27 in accordance with equalizing conditions.

The equalizing beam 27 has a clamping plate 30 by means of which a cable 31, which in this case is a wire cable, is clamped between the receiving grooved portions of said equalizing beam 27 and plate 30. By referring to Fig. 2 of the drawings, it will be noted that the receiving grooves formed 100 in the equalizing beam 27 and clamping plate 30 and therefore the upper part of the cable 31 take a sinuous path for the purpose of preventing the cable from slipping. Preferably the clamping bolts 32 are located 105 at the crimped portions of the cable and over the middle of the springs. The depending portions of the cable 31 terminate in members 32^a which receive the inner ends of equalizing levers 33, which receive their 110

loads from transverse bolster members, as disclosed in my copending application, Serial No. 433,417 filed December 27, 1920. The loads which are transmitted through 5 the equalizing levers 33 are further transmitted through the cable 31, equalizing beam 27, main spring cap 25, auxiliary spring caps 26, springs 21 and 22, directly to the top 18 of the journal box 12. As a result of 10 the auxiliary spring caps or plungers 26 engaging the inner relatively light coil springs 21 and also engaging the equalizing beam 27, equalizing levers 33 are maintained in a horizontal or given position with respect to the journal box and when the car 15 is loaded, the inner coil springs are compressed and thus serve as auxiliary springs. It is apparent from Fig. 1 of the drawings that if the equalizing beam 25 rotates in a 20 counterclockwise direction, the auxiliary spring 21 on the left hand side will be compressed an increased amount, thereby increasing the tendency of said spring to return the associated equalizing lever 27 to a 25 horizontal position if it has moved from such position.

The equalizing beam has downwardly extending side flanges 34, which embrace the side of the main spring cap 25 for holding 30 said parts in their proper relative positions. The vertical passageways 35 formed between the journal box walls 14 and 15 are wide open at each end to give a considerable 35 clearance for relatively wide range of longitudinal movement for the equalizing levers 33 which is occasioned during starting and stopping actions of the car.

It is my intention to cover all modifications of the invention falling within the 40 spirit and scope of the following claims.

I claim:

1. In a railway car truck, the combination of a journal box, springs mounted directly on top of said journal box, a spring cap bridging said springs, an equalizing beam, said cap and beam having a connection whereby one may be rotated on the other, and means operatively connected to said equalizing beam whereby loads may be transmitted to the latter and equalized with respect to said journal box. 45

2. In a railway car truck, the combination of a journal box, resilient means mounted directly on top of same, a member supported on said resilient means, an equalizing beam, said member and beam having a connection whereby one may be rotated on the other, and means operatively associated with said beam whereby loads may be transmitted to the latter and equalized with respect to 60 said journal box. 55

3. In a railway car truck, the combination of a journal box having a main body portion and outwardly extending hollow wings, load carrying springs mounted directly on top of said journal box, and equalizing mechanism operatively associated with said springs and including parts extending through said hollow wings. 65

4. In a railway car truck, the combination of a journal box, equalizing mechanism operatively connected thereto and including an equalizing beam mounted over said box, and a load transmitting cable secured to said equalizing beam in a sinuous path to prevent 75 slipping of said cable. 70

Signed at Chicago, Illinois, this 18 day of April, 1921.

JOHN A. LAMONT.
